(57) **CLAIM**

We claim the ornamental design for an ice hockey puck, as shown and described.

DESCRIPTION

FIG. 1 is a perspective view of an ice hockey puck showing our new design;

FIG. 2 is a side elevational view thereof;

FIG. 3 is an elevational view of the opposite side of FIG. 2; FIG. 4 is a side elevational view rotated 90 degrees from FIG. 2;

FIG. 5 is an elevational view of the opposite side of FIG. 4;

FIG. 6 is a top plan view thereof; and,

FIG. 7 is a bottom plan view thereof.

The appearance within the unshaded areas defined by the circles shown in FIGS. 1, 3, 4, and 5 forms no part of the claimed design.
